UNITED STATES PATENT OFFICE.

JOHN W. COVER, OF SEATTLE, WASHINGTON, ASSIGNOR TO LODE DREDGE CO., OF SEATTLE, WASHINGTON, A CORPORATION OF WASHINGTON.

ORE-GRINDING MILL.

Application filed August 11, 1924. Serial No. 731,280.

To all whom it may concern:

Be it known that I, JOHN W. COVER, a citizen of the United States of America, and resident of the city of Seattle, in the 5 county of King and State of Washington, have invented certain new and useful Improvements in Ore-Grinding Mills, of which the following is a specification.

My invention relates to that kind of a 10 grinding mill employed for grinding ores and other analogous work, commonly referred to as a bar mill, the same employing a series of loose bars or rods confined within a casing and caused to roll and slide upon 15 themselves by revolution of the casing.

The object of my invention is to provide 20 improvements in the detailed construction of such a mill which will facilitate the making and maintenance thereof and its operation.

My invention consists of the novel features which will be first described and then 25 specifically defined in the claim.

The accompanying drawings show my 30 invention in its present preferred form.

Figure 1 is a longitudinal section through a drum having the construction which forms the subject of my present 35 invention.

Figure 2 is a side view of one of the trackway rings.

Figures 3 and 4 are cross sections of alternate forms of construction for the 40 abutment plate or head.

The present invention is an improvement 45 upon the type of mill shown in United States Patent No. 1,242,423, issued to me October 9, 1917. The parts which constitute my invention are included in the construction of the drum and its contents. The 50 entire mounting of the mill has not, therefore, been shown. This may be such as shown in said patent or of any other type found suitable.

The drum 1 is supposed to have screens for 55 the passage of water and finely ground material, either such as shown in said patent or of other suitable construction. Within the drum, and secured thereto, are two trackway 60 rings 2. These are supported inwardly from the drum as by the use of feet or legs 20, clearly shown in Figure 2. Within these trackway rings are placed a bunch of rods or bars as 21.

The material to be ground is introduced

through one or the other of the hollow journals 10 upon which the mill is supported and turned. The drum is provided with ledges or plates 11 extending a short distance inward from the shell, these serving to raise a portion of the ore or other material being ground and depositing it upon the mass of the rods which do the grinding. This is similar in construction to that shown in my 60 said patent.

It has been found that in a rod mill of this type the rods will shift somewhat endwise and will contact with the head of the drum if this be permitted, thereby tending to wear out the head of the drum. To 70 counteract this and for other reasons, I have, in the present invention, provided an abutment head 3 located one in each end of the drum, and have supported these from the 75 drum or the head thereof so that they are separated slightly more than the length of the rods employed. These abutment heads may be made of heavy castings which are easily and cheaply made, as they do not require machine finishing. Therefore, when 80 worn out they may be cheaply replaced. This may be done at much less cost than replacing the true head of the drum.

In the type of construction shown the 85 abutment heads 3 are supported by legs 30 which may be cast integral therewith or attached thereto. These legs, in Figure 1, are shown as extending to and carried by the heads 12 of the drum. Whether carried by the heads 12 or by the outer shell of the 90 drum is immaterial. I have also shown the abutment heads 3 as provided with a central hole of considerable size, in which is secured a smaller head 31. This latter head may entirely close the opening in the head 3 or 95 it may be provided with a central head 32 through which a rod may be inserted for carrying a deflector plate such as is shown in my previously mentioned patent, or a pipe for carrying water.

For convenient insertion and removal of the grinding rods 21, I provide at least one of the abutment heads 3 with an opening, preferably spaced from the center so that its outer edge approximately corresponds 105 with the trackway surface of the rings 2. This opening is also in alinement in the direction of the axis of the drum, with a complementary opening in the head 12 of the drum. It is evident that with holes so 110

placed, of a size to pass the grinding rods, these may be very conveniently inserted and may also be removed without difficulty. Without provision of such means the insertion or removal of these rods after the drum has been assembled would be a very difficult, if not an impossible, matter.

The holes above described are, when the drum is in use, closed by a plug device 10 shown at the right hand end of Figure 1. This device has a head 4 which snugly fits the opening in the abutment head, the inner end face of the plug alining with the inner surface of the abutment head. The shaft 15 40 of this plug connects the head 4 with the head 41 which is so shaped and of such size as to fit the opening in the head 12 of the drum. This may be clamped in place with packing material so as to maintain a 20 water tight joint. By the removal of this plug it is thus possible to extract or replace the grinding rods.

I have illustrated in the drawing the drum 1 as mounted to turn upon hollow 25 journal extensions 10, one at each end. These turn in suitable bearings. The manner of mounting this for turning is, however, immaterial. This may be done by

mounting it upon rollers as was illustrated in my previous patent above referred to. 30

In Figure 1 I have shown the abutment heads 3 as having a plane surface without any flanges at the outer edges. These abutment heads may be constructed after the form shown in Figures 3 and 4, in which 35 flanges as 33 and 34 are shown surrounding the outer edge of the heads. These serve as additional means for retaining the rods in place. The curved flanges 34, when used, will also serve to somewhat crowd the rods 40 toward the central position.

What I claim as my invention is:

In a bar mill, a drum, trackway rings having their trackway surface inwardly spaced from the inner periphery of the 45 drum, abutment disks of smaller diameter than the drum located between the ends of the bar and the drum heads, one of said abutment disks and its adjacent drum head having alined holes permitting passage of 50 the grinding rods and a stopper adapted to close both of said openings and secured to the drum head.

Signed at Seattle, King County, Washington, this 31st day of July, 1924.

JOHN W. COVER.
